COMPOSITION FOR CLEANING HARD SURFACES
Louis McDonald, Altadena, Calif., assignor to Kelite Corporation, Los Angeles, Calif., a corporation of California
No Drawing. Filed June 16, 1958, Ser. No. 742,006
2 Claims. (Cl. 252—137)

This invention relates to the cleaning art and has particular reference to a novel composition and method for cleaning hard surfaces.

The removal of soil from hard surfaces, particularly those hard surfaces which are sensitive to chemical attack, has usually been accomplished by the use of moderately alkaline cleaners embodying agents which inhibit corrosive attack upon the metal surface. For example, compositions made in accordance with U.S. Patent No. 2,381,124 have been successfully employed in cleaning aluminum surfaces without deleterious corrosive attack upon the surface. Such a composition is also successfully used for cleaning bare ferrous metals without corrosive attack or promoting rusting after cleaning.

In the cleaning of hard surfaces which are coated with protective and decorative organic finishes, it is frequently found that mildly alkaline cleaners, even those inhibited against attack on light metal alloys such as aluminum, will cause the finish to streak, bring about loss of gloss and accelerate the deterioration of the organic finish. The cleaning of such surfaces with solutions essentially comprised of organic non-soap detergents, such as alkyl aryl sulphonates, and employed as essentially neutral pH's in the region of 7-8, will also cause streaking of certain organic finishes with accompanying spotting, formation of blemishes and accelerated deterioration. Frequently, too, if the solution of organic non-soap detergent is employed at sufficient concentration to remove oily soils, it will also remove protective waxes. This difficulty is also inherent in the use of mildly alkaline cleaners, even corrosion inhibited cleaners. The problem of cleaning light alloys and hard surfaces finished with protective and decorative organic finishes is prevalent in the washing of vehicles such as automobiles, buses, trucks, airplanes and various and other common articles of commerce which are either fabricated of aluminum and/or which are painted with decorative and protective organic finishes. In the industrial areas of cleaning airplanes and vehicles, such as motor vehicles and buses, a real problem exists. These vehicles are usually polished with wax polishes and they are severely soiled with oily soils, solid dirt from atmospheric fallout and additionally the organic surface or the light alloy surface is frequently oxidized from weathering. To properly clean the surface it is desirable to remove the oily soil and solid dirt and at the same time to reduce or remove the oxide surface. Frequently it is desirable to accomplish this without dewaxing the surface.

This same type of problem is prevalent on a somewhat larger scale in the cleaning of railroad equipment such as railroad passenger cars. Here the practice has been to use rather strongly acid cleaners embodying such agents as sodium bisulphate and employing a cleaning bath operating at levels of pH in the range of 2 and 3. This type of cleaner effectively removes oxidized paint. However, it is not suitable for use on fine organic finishes and for use in conjunction with vehicle components made of aluminum and similar light alloys.

One of the principal objects of the present invention is to provide a novel cleaning composition which is not subject to the above and other disadvantages of the prior art cleaners.

2

More specifically, it is an object of the present invention to provide cleaning compositions adapted to remove soil, and to reduce oxidized finish, from hard surfaces such as aluminum alloys and organic surfaces without corrosive attack, streaking, spotting, dewaxing or other deterioration of the surface being cleaned.

Other objects and advantages of the present invention it is believed will be readily apparent from the following detailed description of preferred embodiments thereof.

Briefly, this invention comprehends within its scope the discovery that compositions embodying a major proportion of ammonium sulphate, which is essentially neutral in terms of pH when dissolved in water in conjunction with certain organic detergents and rinse assistants, will satisfactorily accomplish the desired cleaning of hard surfaces without deleterious effect. The ammonium sulphate appears to function as a complexing agent in a dual capacity. First, it complexes metallic oxides to bring metal ions into solution and to hold them complexed and unreactive. Secondly, the complexing agent serves to promote micelle formation of the organic detergent involved to accomplish effective removal of oily soils and solid dirts without attack on temporary protective finishes such as wax or the organic protective or decorative finish or without attack on the aluminum alloy. Any organic non-soap detergent of the anionic, cationic or nonionic type can be employed as a minor constituent of the composition. Such organic non-soap detergents are well known in the art and are disclosed in many references such as, for example, Sisley et al., Encyclopedia of Surface Active Agents (Chemical Publishing Co.) and Swartz et al., Surface Active Agents (McGraw-Hill). It has been found, however, that specific combinations of long chain anionics of the class of alkyl aryl sodium sulphonate and short chain molecules of the same species are highly effective in the presence of ammonium sulphate in the removal of the specific soils without causing deleterious attack or streaking on the organic finish.

Specifically, alkyl aryl sulphonates having molecular weights of the order of the molecular weight of dodecyl benzene sodium sulphonate and another, lower, alkyl aryl sulphonate having a molecular weight of the order of the molecular weight of naphthalene diisobutyl sodium sulphonate when used in substantially equal weight proportions as minor constituents, with ammonium sulphate as the major constituent, exhibit the optimum cleaning behavior described above. These lower alkyl aryl sulphonates fall into two general classes having generic formulae as follows:

(a)

$$\begin{array}{c} (r_1)_n \\ \diagdown \\ R-X \\ \diagup \\ r_2 \end{array}$$

wherein R is an aromatic ring, X is a member of the group consisting of sulphonic acid and salts thereof, r_1 is an aliphatic group having no more than 5 carbon atoms and n is an integer not more than 2, and r_2 is selected from the group consisting of hydrogen, methyl, and ethyl. Diisobutyl methylnaphthalene sodium sulphonate is a typical example of this class. Other are di-isopropyl naphthalene sodium sulphonate and diisobutyl naphthalene sodium sulphonate.

(b)

$$X-R-(CH_2-R-X)_y$$

wherein R is a naphthalene ring, X is a member of the group consisting of sulphonic acid and salts thereof, and y is an integer from 1 to 6. Compounds within this class are polymeric naphthalene methylene sulphonates. Typi-

cal of this class is polymeric naphthalene tetra methylene sodium sulphonate which is formed by sulphonating naphthalene with a strong sulphonating acid, diluting with water and adding methylene groups by reaction with formaldehyde. Then formaldehyde in the presence of free sulphuric acid initiates polymerization.

It has been further discovered that the formation of water spots, which normally form on rinsing of a detergent bath from the surface cleaned can be eliminated by the inclusion of certain complex molecularly dehydrated phosphates in minor amounts.

Materials which show strong ability to complex—i.e., to form two or more compounds or ions or to form complex groups are found in the general classes of chemical compounds known as the cyanides, ammonia, ammonium, oxonium and similar compounds. It is well known, for example, that simple cyanides will combine to form complex cyanides embodying mixed cations. Similarly, ammonia and ammonium compounds form well known complexes such as nickel ammonium sulphate or cuprous ammonium nitrate. Phosphonium and sulphonium compounds constitute lesser known examples. These materials fall under the general class of compounds that form Werner complexes. Among the most satisfactory for this purpose is the common material ammonium sulphate, and it is believed that this compound functions in the manner of a Werner complex when used in accordance with this invention. Other ammonium compounds, such as diammonium phosphate or ammonium nitrate could be used but are less desirable for reasons of cost or possible hazard.

It has been discovered in substance that the replacement of alkaline cleaning assistants such as sodium silicate, trisodium phosphate, tetrasodium pyrophosphate or sodium carbonate by ammonium sulphate eliminates the attack on light alloy or hard surfaces finished with organic protective and decorative finishes. Similarly, by the embodiment of ammonium sulphate in compositions consisting of organic detergents such as an alkyl aryl sulphate, the cleaning efficiency is improved and the deleterious action of the organic detergent on organic finishes is eliminated.

The compositions are utilized by dissolving in water to form aqueous solutions of concentrations in the neighborhood of ½-2 oz./gallon. The solutions are applied manually with a sponge or mop or brush onto the surfaces to be cleaned. After application the solution and soil is flushed off with a running cold water rinse. It is not necessary to manually wipe the surfaces dry. They will dry by draining and evaporation to leave a bright, unblemished surface.

It is also possible to apply the cleaning solution by spray using the impingement force of the spray to assist in the removal of the soil. Following the spray application the detergent solution and soil are removed by a pressure cold water rinse.

Another method is to clean small parts by immersion in a bath of the detergent solution followed by immersion rinse or spray rinse in the conventional manner.

For reasons of economy and convenience of handling and shipping the compositions are best made as dry powders. It is also possible to commercially furnish such a composition in the form of an aqueous solution or concentrate without departing from the scope or spirit of this invention.

The following specific examples illustrate the compositions and process of the present invention, but it is to be understood that the invention is not to be specifically limited thereto:

Example 1

	Weight percent
Ammonium sulphate	82
Diisobutyl naphthalene sodium sulphonate	7
Dodecyl benzene sodium sulphonate	8
Sodium tripolyphosphate	3

The composition of Example 1 produces an aqueous cleaning solution which is exceptionally free rinsing, is efficient in the removal of oily solids and solid dirt, and leaves both metallic and painted surfaces with a high gloss.

The diisobutyl naphthalene sodium sulphonate functions as an anti-caking agent in addition to furnishing a strong wetting component which causes the foam to break rapidly, disperses the solid dirt and influences the rapid rinsing characteristics of the composition.

It is possible to utilize a composition similar to the above without the inclusion of a complex molecularly dehydrated phosphate such as sodium tripolyphosphate, sodium tetraphosphate, sodium pentametaphosphate or sodium hexametaphosphate. It is found, however, that the embodiment of minor amounts of these complex phosphates improve rinsability and eliminate deposition of water spots from hard water salts. The use of complex phosphates such as tetrasodium pyrophosphate or orthophosphates such as trisodium phosphate is not feasible due to the increase in alkalinity and pH that they contribute to the cleaning bath. However, primary and secondary orthophosphates such as monosodium phosphate or mono and diammonium phosphates could be desirably employed.

The cleaner baths of the present invention operate satisfactorily without deleterious effect on aluminum alloys or organic finishes over the range of pH of 4.2-7.6.

Very simple, but satisfactory anionic detergent-containing compositions within the scope of the present invention are as follows:

Example 2

	Weight percent
Dodecyl benzene sodium sulphonate	10
Ammonium sulphate	90

Example 3

	Weight percent
Diisobutyl naphthalene sodium sulphonate	10
Ammonium sulphate	90

The following example illustrates the use of a cationic detergent:

Example 4

	Weight percent
Dimethylbenzyl cetyl ammonium chloride	10
Ammonium sulphate	90

Example 5 represents the use of a nonionic detergent:

Example 5

	Weight percent
"Triton" X-100	10
Ammonium sulphate	90

The "Triton" detergent of the above Example 5 was an alkyl phenol ethylene oxide condensate having 3-7 ethoxy groups.

The proportions of the compositions of the invention may be varied within rather wide limits. Preferred proportion ranges are as follows:

	Weight percent
Ammonium sulphate	40-97
Non-soap organic detergent	3-60
Phosphate	0-5

Having fully described my invention, it is to be understood that I do not wish to be limited to the details set forth, but my invention is of the full scope of the appended claims.

I claim:

1. A cleaning composition for hard surfaces consisting essentially of 40 to 97 percent by weight of ammonium sulphate and 3 to 60 percent by weight of an organic detergent mixture comprising approximately equal proportions by weight of diisobutyl naphthalene sodium sulphonate and dodecyl benzene sodium sulphonate.

2. The composition of claim 1, wherein the composition includes a minor proportion of sodium tripolyphosphate.
